United States Patent Office

Des. 192,771
Patented May 8, 1962

192,771

BOAT

Leonard E. Greenberg, 195 Brewster Road,
West Hartford, Conn.

Filed June 22, 1961, Ser. No. 65,691

Term of patent 14 years

(Cl. D71—1)

FIG. 1

FIG. 2

FIG. 3

FIG. 4

FIG. 5

FIG. 6

FIG. 7

FIG. 1 is a perspective view of a boat embodying my new design;

FIG. 2 is a top plan view;

FIG. 3 is a bottom plan view;

FIG. 4 is a side elevational view;

FIG. 5 is a front elevational view;

FIG. 6 is a rear elevational view; and

FIG. 7 is a transverse sectional outline of the boat along the line 7—7 of FIG. 2.

The dominant features of my design reside in the full-line portions of the drawing.

I claim:

The ornamental design for a boat, as shown and described.
